(57) **CLAIM**

The ornamental design for a set of multifunction tool components, as shown and described.

DESCRIPTION

FIG. 1 is a front elevational view of a set of multifunction tool components showing my new design consisting of twelve components;

FIG. 2 is a rear elevational view thereof;

FIG. 3 is a perspective view thereof;

FIG. 4 is another perspective view thereof;

FIG. 5 is an exploded view showing eight of the components of the set of multifunction tool components of FIG. 1 in an exemplary configuration of use;

FIG. 6 is a perspective view of the components of FIG. 5 in an assembled condition;

FIG. 7 is another perspective view thereof;

FIG. 8 is an exploded view showing four of the components of the set of multifunction tool components of FIG. 1 in another exemplary configuration of use;

FIG. 9 is a perspective view of the components of FIG. 8 in an assembled condition;

FIG. 10 is another perspective view thereof;

FIG. 11 is an exploded view showing five of the components of the set of multifunction tool components of FIG. 1 in another exemplary configuration of use;

FIG. 12 is a perspective view of the components of FIG. 11 in an assembled condition;

FIG. 13 is another perspective view thereof;

FIG. 14 is an exploded view showing three of the components of the set of multifunction tool components of FIG. 1 in another exemplary configuration of use;

FIG. 15 is a perspective view of the components of FIG. 14 in an assembled condition; and,

FIG. 16 is another perspective view thereof.

The dash-dash broken lines illustrate environmental subject matter only and form no part of the claimed design.
